AUTOMOBILE ANTI-TAMPERING AUDIBLE ALARM

Robert D. Kahn, Rockville Centre, N.Y., assignor to Fedtro, Inc., Rockville Centre, N.Y., a corporation of New York

Filed Feb. 9, 1968, Ser. No. 10,516

Term of patent 14 years

Int. Cl. D29—99

U.S. Cl. D72—1

FIG. 1 is a front perspective view of the automobile anti-tampering audible alarm;

FIG. 2 is a top plan view thereof;

FIG. 3 is a left side elevational view thereof;

FIG. 4 is a right side elevational view thereof;

FIG. 5 is a rear elevational view thereof; and

FIG. 6 is a bottom plan view thereof.

I claim:

The ornamental design for an automobile anti-tampering audible alarm, as shown and described.
